CLAIM

The ornamental design for a solar floodlight, as shown and described.

DESCRIPTION

FIG. 1 is a front view of a solar floodlight, showing our new design;

FIG. 2 is a back view of the solar floodlight shown in FIG. 1;

FIG. 3 is a left side view of the solar floodlight shown in FIG. 1;

FIG. 4 is a right side view of the solar floodlight shown in FIG. 1;

FIG. 5 is a top view of the solar floodlight shown in FIG. 1;

FIG. 6 is a bottom view of the solar floodlight shown in FIG. 1;

FIG. 7 is a front perspective view of the solar floodlight shown in FIG. 1;

FIG. 8 is a back perspective view of the solar floodlight shown in FIG. 1;

FIG. 9 is a cross section view taken along lines 9-9 of FIG. 1; and,

(Continued)

FIG. 10 is a cross section view taken along lines 10-10 of FIG. 1.

The portions of the solar floodlight shown in broken lines form no part of the claimed design.

1 Claim, 8 Drawing Sheets
